UNITED STATES PATENT OFFICE.

LEWIS T. RHOADES, OF MONT CLARE, PENNSYLVANIA, ASSIGNOR TO NEW YORK COIL COMPANY, OF NEW YORK, N. Y.

COIL SUPPORT.

Application filed June 11, 1923. Serial No. 644,723.

To all whom it may concern:

Be it known that I, LEWIS T. RHOADES, a citizen of the United States, residing at Mont Clare, in the county of Montgomery and State of Pennsylvania, have invented certain new and useful Improvements in Coil Supports, of which the following is a specification.

My invention relates to supports for coil windings of a type particularly adapted for use in radio apparatus. Heretofore, the supports used for holding coils have been of a type which requires solid dielectric material disposed within the magnetic field and between the coils, or between the coils and a magnetic core or other parts adapted to receive an induced current from the coils, or of a type in which air was employed as the dielectric. The solid dielectric disposed between the coils is objectionable because its insulation is imperfect and some electric current passes between the inner and outer coils. It is also objectionable because it is an imperfect conductor of magnetic waves and because its conductivity varies throughout its mass and this non-uniformity causes hysteresis. The presence of solid dielectric material within the magnetic field and contact of such material with any part of the coils is objectionable, and therefore the solid material and the contact should be reduced to the minimum. Air is the ideal dielectric but its use involves a problem as to mounting and spacing the coils which, so far as I am aware, has never been adequately solved.

The objects of my invention are to supply a support for coils in which there is no solid dielectric material between the coils, in which the solid dielectric material within the magnetic field and the contact of such material with the coils are reduced to the minimum, and to provide a simply constructed support which may be easily assembled and the coils properly and efficiently spaced by any unskilled person of ordinary intelligence.

These objects, and other advantageous ends which will be described hereinafter, I attain in the following manner, reference being had to the accompanying drawings in which—

Figure 1 is a side elevation of a radio instrument, known as a transformer, constructed in accordance with my invention.

Figure 2 a top plan view of Figure 1. 55
Figure 3 a section on line 3—3 of Figure 2.

Figure 4 a section on line 4—4 of Figure 1, and

Figure 5 a perspective view of a coil 60 holder which forms a part of my invention.

Referring to the drawings, 1 indicates my improved coil support which includes two plates 2 preferably stamped from insulating sheet material of substantially rectangular form, and hereinafter called coil holders. Two opposing edges of each coil holder are cut away to form comparatively long recesses 3, adapted to receive an outer coil 5, and shorter recesses 4, extending inwardly from the long recesses, adapted to receive an inner coil 6 of comparatively small length and diameter. The longitudinal edges 7 of recess 3 engage the inner periphery of the longer coil and serve to support 70 it while the shoulders 8 hold the coil against movement in the direction of its axis. The longitudinal edges 9 of the inner recess engage the inner periphery of the smaller coil and serve to support it while the shoulders 80 10 hold it against movement in the direction of its axis.

To hold the edges 7 and 9 in engagement with the windings of the coils 5 and 6, I provide spacers 11 disposed between the coil 85 holders near their upper and lower edges. A bolt 12 passes through each spacer 11 and the coil holders 2 to rigidly connect the coil holders and securely hold them in engagement with the windings of the coils, 90 thus keeping the coils properly spaced relatively to each other. Terminal posts are secured to the coil holders in any suitable position, preferably as shown at 13, for electrically connecting one end of the large coil 95 5, at 14 for connecting the other end of the large coil, at 15 for connecting one end of the small coil 6 and at 16 for connecting the other end of the small coil.

To hold my improved support in a proper 100 position relatively to other instruments in radio apparatus I provide a pair of short

brackets 17 secured to the lower edge of one of the coil holders by screws or the like and a long bracket 18 secured to the lower edge of the other coil holder by the bolt 12. 5 These brackets hold the support in an inclined position so that the electrical influence from other instruments on the coils 5 and 6 will be reduced to a minimum.

In assembling an instrument having my 10 improved support the coils are first wound on a collapsible mandrel. A coating of hardening material of any suitable description such as shellac is applied to keep the windings together. The coils are then removed 15 from the mandrel and placed in position on the coil holders as shown in Figures 3 and 4. The spacers are then placed between the coil holders and the bolts 12 passed through the spacers and coil holders 20 and secured thereto. The terminal posts are then electrically connected to the ends of the coils and the brackets secured to the lower edges of the coil holders. The instrument is then ready for use.

25 In my improved coil support, there is no solid dielectric material between the coils, the dielectric material within the magnetic field is reduced to the minimum, the contact of the coils with dielectric material is also 30 reduced to the minimum, and the parts are easily assembled and securely held in proper spaced relation. The coil holders may be stamped from sheet material and all holes and recesses formed in one operation at 35 much less cost than the tubes heretofore used and with a considerable saving of insulating material, and the construction is highly efficient.

While I have described my invention as taking 40 a particular form, it will be understood that the various parts of my invention may be changed without departing from the spirit thereof, and hence I do not limit myself to the precise construction set forth, 45 but consider that I am at liberty to make

such changes and alterations as fairly come within the scope of the appended claims.

Having thus described my invention, what I claim as new and desire to secure by Letters Patent is:—

1. A coreless coil support consisting of a pair of coil holding plates of insulating material, each plate having recesses for receiving coils of different diameter, and means for spacing and connecting the holding 55 plates.

2. A coreless coil support consisting of a pair of coil holding plates of insulating material, each plate having recesses for receiving coils of different diameter, the recesses 60 extending edgewise of the plates, the length of one recess being equal to the width of the outer coil, and the length of another recess being equal to the width of the inner coil, and means for spacing and connecting 65 the holding plates.

3. A coil support consisting of a pair of coil holding plates, each plate having recesses for receiving coils of different diameter, the recesses extending edgewise of the 70 plates, the length of one recess being equal to the width of the outer coil and the length of another recess being equal to the width of the inner coil, and means for spacing and connecting the holding plates.

4. A coil support consisting of a pair of coil holding plates, each plate having recesses of different depth, the length of the recesses being edgewise of the plates whereby the plates are adapted to receive coils of 80 different diameter, each coil having its windings laterally parallel, and means for spacing and connecting the holding plates.

In testimony whereof I have signed my name to this specification in the presence 85 of two subscribing witnesses.

LEWIS T. RHOADES.
